UNITED STATES PATENT OFFICE.

AUGUST KNÜPFER, OF DORNDORF, NEAR DORNBURG, GERMANY.

DRILL-MACHINE.

SPECIFICATION forming part of Letters Patent No. 410,692, dated September 10, 1889.

Application filed August 8, 1888. Serial No. 282,233. (No model.)

To all whom it may concern:

Be it known that I, AUGUST KNÜPFER, a subject of the Grand Duke of Saxe-Weimar, and residing at Dorndorf, near Dornburg, in 5 the State of Saxe-Weimar, in the German Empire, have invented certain new and useful Improvements in Drill-Machines, of which the following is a specification.

My invention relates to the manner of fastening the pole to drilling or sowing machines.

In order to make my invention more clear, I refer to the accompanying drawings, in which similar letters denote similar parts throughout the different figures.

15 Figure 1, Sheet I, is a top view of my improved manner of fastening the pole to drill-machines. Fig. 2 is an under view of the locking mechanisms for the same. Fig. 3 is a vertical section through the line $\alpha \beta$, Fig. 1. 20 Fig. 4 is a top view, on a larger scale, of the locking mechanism. Figs. 5, 6, and 7, Sheet II, show a modification of the construction.

The construction is as follows: The hind part of the machine is fastened to fore part 25 by the bar v , hinged to the same by the king-bolt c . The king-bolt c projects through the cross-beam m , and to this cross-beam m is the fifth-wheel f fastened. The pole n is hinged to the king-bolt c and bears with the rollers 30 $r r$ on the "fifth-wheel" f .

In order to fasten the pole n fast when go-

ing round sharp corners or on the road, I provide a catch o under the iron frame e , in which the pole n is held. The catch o , guided in the guides $s s$, is pressed by the spring t 35 into the slot u in fifth-wheel f . The catch o is thrown out of gear by the segment p' catching on the pin p , the slot in the segment p' being eccentric to the center of revolution. The segment is operated by hand by means of the 40 handles $b b$.

Figs. 5, 6, and 7, Sheet II, show a modified construction, in which the pole n may be turned round the bolt w in a vertical direction. All other parts of the construction are the very 45 same and work in the same manner.

Having now fully described my invention, what I desire to claim, and secure by Letters Patent in the United States, is—

In drill-machines, the combination of the 50 frame e , pivoted at w to the king-bolt c , and having fixed to it the bar n , a catch o , and spring t , with the fifth-wheel f , having a slot u , and with the sector p' , having handles b , substantially as and for the purpose described. 55

In testimony whereof I have signed my name to this specification in the presence of two subscribing witnesses.

AUGUST KNÜPFER.
